UNITED STATES PATENT OFFICE.

DAVID ANDERSON, OF WESTCLIFF-ON-SEA, ENGLAND.

INCANDESCENT MANTLE AND BURNER THEREFOR.

No. 011,360.

Specification of Letters Patent.

Patented Feb. 2, 1908.

Application filed February 28, 1906. Serial No. 303,429.

To all whom it may concern:

Be it known that I, DAVID ANDERSON, of Cotswold Cottage, Cotswold Road, Westcliff-on-Sea, in the county of Essex, England, engineer, have invented certain new and useful Improvements in or Relating to Incandescent Mantles and Burners Therefor.

This invention relates to improved inverted incandescent mantles and improved inverted gas burners therefor.

According to this invention the improved mantle is constructed in the form of a comparatively wide shallow cup-shaped annulus (preferably continuous) formed with a central hole and having its concave surface uppermost. The burner head is constructed to discharge the combustible mixture of gas and air in the form of an annular jet in a downward and more or less outward direction into the annular mantle by a continuous annular opening or by a series of openings or tubular projections intermediate between the smaller and larger circumferences of the mantle in such manner that by reason of the direction of discharge combined with the up-draft, the normal flame will have a relatively wide annular shallow cup-shaped form with its convex surface downwards and outwards, whereby the convex surface of the flame will sweep radially over approximately the entire concave upper surface of the mantle, the flame or products of combustion issuing between the outer circumference of the mantle and the circumference of the burner head so that the flame in normal operation of the burner will not pass through the wall of the mantle. In some forms the supply may be from one or more tubes passing to or directing the gas, in the manner and direction referred to, to the interior of the annular mantle.

I have illustrated some forms of my invention in the accompanying drawings.

Figure 1 is a sectional elevation of the improved inverted burner, supported from below. Fig. 2 is a sectional under side view showing only the burner head and tube as seen from the plan indicated by the line A—B in Fig. 1. Fig. 3 is a similar view to Fig. 1 of a modified construction adapted as a burner supported from above. Fig. 4 is a similar view to Fig. 3 of a modification. Fig. 5 shows a further modified construction. Fig. 6 is a section of Fig. 5 on line C—D. Fig. 7 is a part view of Fig. 5 showing the means whereby same can be supported from

below. Fig. 8 is a part view in vertical cross section of a modified form of mantle and burner head. Fig. 9 is a central vertical section partly in elevation of a modified construction of the improved burner, and Fig. 10 is a similar view of a further modified construction of the improved burner.

In Figs. 1 and 2 an inverted burner is shown wherein the burner head or body part 65 thereof *a* is in the form of a hollow casing somewhat in the form of a disk or of mushroom shape being partly spherical on the upper side and having a tube *b* opening into it at its under side the tube being spread to 70 form the underside *b'* of the body part which terminates at a suitable distance from the edge of the portion *a* so as to leave an annular space *c* between the parts *a* and *b'* which annular space forms the aperture by which the 75 gas and air issue in a downward direction within the mantle *d*. The downward direction of discharge combined with the up-draft will produce a comparatively wide 80 annular flame of shallow cup-shape having its convex surface downwards and outwards. The mantle *d'* is formed in cross section to conform to the shape of the annular flame. That is to say it is in the form of a comparatively wide shallow cup shaped annulus 85 adapted to surround the tubular part *b* which passes through a hole in the mantle, the outer edge of the mantle is fastened to a ring *e* which ring is supported from the body part *a* of the burner in the usual manner by 90 lugs *f* engaging with recessed lugs *g* upon said body part. The ring *e* is spaced a suitable distance from the body part *a* so as to allow of the products of combustion from the flame passing up between same. Within the body 95 part *a* is mounted a perforated shield *h* disposed above the supply pipe *b* and a spreading cone *i* may be provided if required to secure an even distribution of the gas and air. The shield *h* may serve as a means for coupling the 100 parts *a* and *b* of the body part together by means of a screw, such as *j*. The body part of the burner is mounted upon the upper end of an ordinary air and gas mixing chamber *k* with the usual tubular extension *l*.

In operation it will be seen that the gas and air from mixing chamber *k* passes up the tube *b* and issues into the annular shallow cup-shaped mantle *d* by the continuous annular opening *c* the flame passing downwardly in the form of an annulus and then passing upwardly and outwardly against the

mantle toward the space between the ring *e* and the body part *a* although it may in some cases with excessive gas pressure also pass outside and around the mantle. The mantle 5 when in use will thus present an annulus of light disposed beyond the tube *b* and mixing chamber *k* by which the mantle is supported from the gas supply pipe, and by reason of the mantle being beyond the support any appreciable shadow will be avoided and a better 10 distribution of the light will be insured. If the said burner is desired to be supported from above with an over-head gas supply the construction may remain very much the 15 same as regards the disk like body part and mantle as will be seen by reference to Fig. 3 which shows a modification of this kind. In this arrangement the perforated shield and spreading cone such as usually employed in 20 burners are inverted and the upper part of the burner is provided with a reflector *o* around the tubular extension from the air and gas mixing chamber *a*. The open end of the tube *b* is closed by a suitable plug *p* 25 which if required may serve to support a gallery *q* by means of downwardly extended rod *r*, the said gallery carrying a globe *s* of suitable shape.

In Fig. 4 I have shown another form of the 30 improved burner supported from above. In this form the gas supply is introduced at the top of the body part *a* by means of a pipe *t* which is projected through the body part by an extension *t'* which terminates at or about 35 the entrance of the lower air supply tube *b*, the pipe *t'* is fitted at its lower end with a suitable upwardly directed nozzle such as *u* which consists of a cap of slightly larger dimensions than the end of the tube *t'* so as to 40 allow of the gas jets being formed in its upper edge as at *w*. These gas jets *w* are adapted to direct the gas supply upwards into the air tube *b* in such manner that the gas and the air in the air supply tube will 45 mix in the interior of the pipe *b* and the body part *a* and then issue by the annular nozzle *c* to the interior of the mantle in the manner as previously described.

The globe shown may be supported in any 50 suitable manner from above or below the burner. Fig. 4 shows the globe *s* supported from above by means of a ring *z*. Where the globe is entirely closed at its lower end it may be desirable in some cases to provide an annular shield *y* to receive and direct the upwardly flowing hot air on the one side and allow the inflowing cold air to pass freely down against the globe on the other side of the shield.

60 The body part *a* of the burner may be made of porcelain or a suitable kind of earthenware or refractory material.

Fig. 5 shows a construction similar to Fig. 4 but wherein the lower portion of the tube 65 *b* is fitted with a downward extension *b'* of

considerable length so as to open at a distance from the burner or outside the globe or shade *z*, said shade or globe being if required supported as shown by the lower end of the tube portion *b'*. The portion *b'* and the globe 70 being secured by a nut such as *l* attached to the nozzle *u* whereby on unscrewing the nut the globe and the lower part *b'* of the tube *b'* may be detached whereby also a new mantle 75 may be put into position. In this construction the entire supply of air is drawn from outside the globe.

It will be obvious that the constructions shown in Figs. 4 and 5 may be readily adapted to a burner obtaining its gas supply from below, it being only necessary to close the upper end of the tube *t* by a suitable cap and fit a nozzle at *u* so modified that it may be connected to an ordinary gas supply pipe as shown in Fig. 7 and if desired the tube portion *b'* may be divided into various parallel longitudinal divisions forming a set of tubes corresponding with the gas jets from the nipple beneath as shown in a section in Fig. 6.

In a modified construction shown in Fig. 9 80 the improved burner comprises a central tube 2 screwed at its end as at 3 and having central holes 4. Fitting around this tube 2 are two disk-like members 5, 6, disposed one above the other and spaced apart by a central collar or sleeve 7 which surrounds the holes in the tube 2 so as to allow the gas to pass therefrom into the body of the burner wherefrom it issues through the annular opening 8 between the parts 5 and 6. The 85 members 5 and 6 are covered by metal shield plates 9 and 10 which are screwed upon the ends of the tube 2. The upper shield is formed with lugs for supporting the mantle as at 11. A cap 12 is provided adapted to 90 fit either end of the tube 2, whereby a burner such as described may be coupled to a gas and air supply fitting such as 13 at either its upper or lower end to form respectively an inverted or upright burner. The cap will be 100 placed over the end which is opposite the gas supply, and if a by-pass is required it may be provided by passing a tube through the tube 2 and into the cap 12, the cap being provided 110 with a suitable passage leading to a by-pass burner tube suitably disposed in regard to the burner.

Fig. 10 shows a construction similar to Fig. 9 where the disk-like members are dispensed with, the body part being formed of two members 17 and 18 screwing upon the central tube and having a perforated metal sleeve 19 disposed around the apertures in the central tube or otherwise fitted thereto.

I wish it to be understood that the annular discharge orifice in the burner head whence the flame issues need not be continuous but may consist of a series of openings or holes or it may be composed by a series of tubular projections opening in the mantle. The 125 130

body part of the burner may in some cases be in the form of an annulus as that part where the flame issues, the supply being connected thereto from a central supply or a central 5 mixing chamber.

The invention allows of mantles being made which will give high candle power. For such mantles it is desirable that the discharge be inclined more outwardly, the 10 amount of inclination being a matter of design in relation to the pressure. One form of this is illustrated in Fig. 8, where the mantle is more flattened in order to conform to the shape of the more outwardly inclined 15 flame.

What I claim and desire to secure by Letters Patent is—

1. In burners for incandescent gas lighting the combination of an inverted burner head 20 having a discharge aperture of continuous annular form in plan, and a relatively wide inverted annular mantle of shallow cup shape located with its concave internal surface next to said burner head, supply apertures and connections fitted both above the 25 burner head and centrally below the same whereby the same burner head may be supplied with gas either from above or below as desired.

30 2. In burners for incandescent gas lighting the combination of an inverted burner head having a discharge aperture of continuous annular form in plan, and a relatively wide inverted annular mantle of shallow cup 35 shape located with its concave internal surface next to said burner head, supply apertures and connections fitted both above the burner head and centrally below the same whereby the same burner may be supported 40 and supplied with gas either from above or below as desired.

3. In burners for incandescent gas lighting the combination of an inverted burner head 45 having a discharge aperture of continuous annular form in plan, and a relatively wide inverted annular mantle of shallow cup shape located with its concave internal surface next to said burner head, means for supporting the outer edge of the mantle centrally away from the burner head whereby 50 an intermediate annular space is formed which allows the products of combustion to issue between the outer edge of the mantle and the burner head, a gas supply pipe passing downwardly through the burner head, upwardly directed gas jets at the termination 55 of said supply pipe and an opening in the base of the burner head admitting an air supply thereto through the central aperture 60 in the mantle.

4. In burners for incandescent gas lighting the combination of an inverted burner head having a discharge aperture of continuous 65 annular form in plan, and a relatively wide inverted annular mantle of shallow cup

shape located with its concave internal surface next to said burner head, and means for supplying gas and air to said burner from beneath the same centrally through the hole in the annular mantle. 70

5. In burners for incandescent gas lighting the combination of a comparatively wide inverted annular mantle of shallow cup shape with a central hole, located with its concave surface uppermost, an inverted 75 burner consisting of upper and lower disk like members having a through central aperture and adapted to produce when assembled a comparatively wide annular flame of shallow cup shape said flame being directed 80 downwardly and outwardly and then upwardly and directing the flame over the concave inner surface of said mantle, a perforated sleeve joining the two said members together and forming a continuation of the 85 two through apertures therein a tube passing through the central aperture of the body part and projecting from either end thereof and having holes in its side communicating with the interior of the body part through the perforated sleeve, metal shield plates fitting upon and supporting said disk-like members and fastened to the ends of said central tube, means for supporting the mantle from the upper shield plate, a gas and air supply connection adapted to be coupled to one end of 90 said through tube and a cap for closing the opposite end. 95

6. In burners for incandescent gas lighting the combination of a comparatively wide 100 inverted annular mantle of shallow cup shape having a central aperture located with its concave surface uppermost, an inverted burner head consisting of upper and lower disk like members having a through central aperture and adapted to produce when assembled a comparatively wide annular flame of shallow cup shape, said flame being directed 105 downwardly and outwardly over the concave inner surface of said mantle, a perforated 110 sleeve joining the two said members together and forming a continuation of the two through apertures therein a tube passing through the central aperture of the body part and projecting from either end thereof and having holes in its side communicating 115 with the interior of the body part through the perforated sleeve, metal shield plates fitting upon and supporting said disk-like members and fastened to the ends of said central 120 tube, means for supporting the mantle from the upper shield plate, a gas and air supply connection adapted to be coupled to one end of said through tube and a cap for closing the opposite end, a by-pass tube passed centrally through said central tube and coupled to by-pass tubes and passages in and supported by the cap at the other end. 125

7. In burners for incandescent gas lighting, an inverted burner head comprising the 130

combination of a central tube having apertures in its side midway of its length, two disk-like members forming the top and bottom of a mushroom shaped burner head and screwing upon the opposite ends of said tube, a perforated tube disposed within the body part between the two members and surrounding the aperture in the central tube, the outer edge of the two members forming the 10 annular flame opening, a cap for closing one end of said through tube and a gas and air supply connection adapted to be fitted to the other end of the said tube, a comparatively wide inverted annular mantle of shallow cup 15 shape supported by said burner head with the concave inner surface of the mantle uppermost and in approximate coincidence with the convex outer surface of the flame.

8. In burners for incandescent gas lighting an inverted burner head comprising the combination of a central tube having apertures in its side midway of its length, two disk-like members forming the top and bottom of a mushroom shaped inverted burner head and screwing upon the opposite ends of said tube, a perforated tube disposed within the body part between the two members and surrounding the aperture in the central tube, the outer edge of the two members forming 25 the annular flame opening, a cap for closing one end of said through tube and a gas and air supply connection adapted to be fitted to the other end of the said tube, a comparatively wide inverted annular mantle of shallow cup shape 30 having a central aperture surrounding said through tube, means for supporting said mantle from the burner head with the concave inner surface of the mantle in approximate coincidence with the convex outer surface of the flame.

convex outer surface of the flame, a by-pass tube passed centrally through said central tube and coupled to by-pass tubes and passages in and supported by the cap at the other end. 40

9. In a burner for incandescent gas lighting the combination of a body part consisting of a central tube having screwed thereon at 45 its opposite ends two shield plates adapted to support between them two disk-like members forming the chamber of an inverted burner head between them, a perforated tube spacing the said disk-like members apart 50 around the through tube, holes in the through tube to allow the gas to pass therefrom through said perforated sleeve to the burner head, an inverted annular burner opening formed between the outer extremities of the 55 said disk-like members, a cap for closing one end of said through tube and a gas and air supply connection adapted to be fitted to the other end of said tube, a comparatively wide inverted annular mantle of shallow cup shape 60 having a central aperture surrounding said through tube, means for supporting said mantle from the burner head with the concave inner surface of the mantle in approximate coincidence with the convex outer surface of the flame. 65

In witness whereof, I have hereunto signed my name in the presence of two subscribing witnesses.

DAVID ANDERSON.
